[57] CLAIM

The ornamental design for a food tray, as shown and described.

DESCRIPTION

FIG. 1 is a perspective view of the top, front and one side of a food tray showing my new design;

FIG. 2 is a top plan view thereof;

FIG. 3 is a bottom plan view thereof;

FIG. 4 is a front elevation view thereof, the rear elevation view being a mirror image thereof; and,

FIG. 5 is a side elevation view thereof, the opposite side elevation view being a mirror image thereof.
